N. BANGS WILLIAMS, OF PROVIDENCE, RHODE ISLAND.

Letters Patent No. 81,051, dated August 11, 1868.

IMPROVEMENT IN OIL-CUP.

The Schedule referred to in these Letters Patent and making part of the same.

TO ALL WHOM IT MAY CONCERN:

Be it known that I, N. BANGS WILLIAMS, of the city and county of Providence, and State of Rhode Island, have made certain Improvements in Oil-Cups for lubricating machinery; and I give the following description of the same, illustrated by the accompanying drawings, which are referred to herein by the letters and figures marked thereon.

The object of my invention is to make an oil-cup that shall filter the oil from impurities, and by the simplest adjustment vary the flow of the oil to suit the requirements of the different classes of journals and machines to which it may be applied, and also to suit the different densities of the oils which are used, and at the same time to have the parts easily accessible for adjustment and cleaning, and yet so secure in their attachments that the concussions and violent motions of machinery will not change their relation to each other, so that an equable supply of oil is assured. Nor will the parts be thrown off, as is frequently the case in locomotives, crank-pins of stationary engines, saw-mills, and the journals of fan-blowers, and machines of like character.

Description of Drawings.

Figure 1 is a side view of a locomotive oil-cup, as it appears externally. A A is the body of the cup, made of any suitable metal. B is the stem by which it is attached to the machine. C is the cover, and E a thumb-screw, the office of which will be shown further on.

Figure 2 is a view of the cup in vertical section. A A, the body of the cup, the mouth of which is threaded to receive a corresponding male thread on the cover C. D is a bolt, which slides back and forth in the cover. E is a thumb-screw passing through the slot e in the cover, into the central part of the bolt D, which is threaded to receive it, and projecting far enough to take on the washer a, this washer allowing about half a turn to the screw E. One arm of the bolt D is mounted with the spiral spring H, to throw the bolt forward. The other arm of the bolt extends a little way beyond the male screw of the cover, moving in a slot cut in the screw to receive it, as seen in Figure 4. This slot is made from a hole which is drilled through the rim of the cup and the cover, after this latter has been screwed firmly into place, so that these two openings exactly correspond.

The end of the bolt D, where it comes through the screw on the cover, is inclined on its lower margin, and comes a little way below the screw of the cover. The object of this chamfer or incline is, that when the male screw enters the threads in the mouth of the cup, and is turned round, the bolt D is pressed back and does not interrupt screwing the cover into place. When this is done, the bolt shoots forward into the opening or hole in the rim of the cup, and holds it firmly. To make it still more secure, the screw E is turned hard down, and jar and concussion will not loosen it, nor violent motion throw it off.

To remove the cover, the screw E is loosened, the bolt slipped back by pressure on the screw E, and the cover turned out. As the end of the bolt rises above the hole in the rim of the cup, it of course does not catch nor interrupt the unscrewing of the cover. The end of the bolt in its seat is seen in fig. 1 at D.

I now come to the device for filtering the oil and regulating the supply to the journal. This is shown mainly in section in fig. 2. The stem B of the oil-cup is provided with an oil-duct, I, through its centre. This is threaded throughout its length to receive the screw F. This screw has a flat, round head, about the size given in the drawing, upon which is a thumb-piece, and a slot in this for a screw-driver. The shaft of the screw has a slot cut from its point nearly its whole length, this slot being deeper at the point and growing shallower near the head. e, in Figures 2 and 5, give two views of this slot. The object of this taper is to diminish the passage for the oil to the journal as the screw is turned down in its seat in the stem of the cup, and to enlarge it as it is turned up.

The point of the screw F is split for about half an inch, and then sprung slightly apart, (seen at d, figs. 2 and 5.) This is to make the screw secure in the oil-duct at whatever place it may be put, so that when the flow is properly graduated, it may not be changed by the jar and concussion of the machine upon which the cup is placed.

Upon the shaft of the screw F, disks of fibrous material, punched out with a hole in the centre, (see Figure 3,) are placed one upon the other, as seen at G G, fig. 2, and through these disks all the oil is filtered before it can pass into the journal through the channels already described. More pressure upon the disks lessens the flow through them, and it lessens at the same time the size of the orifice through which the oil passes into the duct I.

These disks may be made of woollen or cotton cloth, felt cloth, cotton flannel, bibulous paper, or may be punched from cotton wadding or porous pasteboard, and in practice it is found that, whether the cup is full or the oil low, the supply to the journal remains the same, the capillary attraction of the fibrous disks taking up the oil and giving it through the duct in the screw at an equable rate.

These devices enable me to adjust the cup so nicely that a drop forming on the end of the duct I, will remain there when the machine is still, and when taken off by the suction caused by the rotation of the shaft, another will form, and this more or less rapidly, as the regulating-screw is out or in.

Where a very thin oil is used, I lessen the number of fibrous disks by slipping upon the shaft of the screw one or more disks of wood, as seen at J J in Figure 6. This is only necessary, however, in those cases where the stem B is cut so short to attach it to the machine, that the end of the screw F would rest on the journal when turned down sufficiently to compress the fibrous disks.

The above description of the various parts makes the operation so plain that further remarks are deemed unnecessary, and it will be seen that the objects of my invention are carried out in a simple and effectual manner.

No particular skill is required in packing the cup; all the parts are easily accessible for adjustment and cleaning, and they all remain in the desired position, not being disturbed by concussion or motion.

I am aware that a spring-clutch, locking into a flange upon the wick-tube of the ordinary wick-cup, has been used to secure the cover of an oil-cup, but this device was ineffectual in practice.

I am aware, also, that oil-cups have been packed with fibrous material contained in tubes or chambers, and compressed therein by a screw, and by a screw and tapering spindle combined; and that a screw, in combination with a winged nut, a perforated disk, and a sponge between this and the oil-duct, has been used, as in the patent of E. Wersenbone, January 17, 1865.

As, also, that a slotted screw, in which the slot is cut nearly the depth of the threads in the male screw, and the female screw in the duct slotted in the same manner, operating like a stop-cock when the slots are turned away from each other, as seen in the patent of Charles Andrew, November 7, 1865; the screw here being placed on the under side of the stem of the cup.

I, therefore, do not claim any of the devices to which I have referred.

The difficulty in the use of fibrous material in masses is, first, that it requires much skill and labor to pack the cup so that it operates satisfactorily; second, when this is used in tubes and chambers, and compressed therein, by a screw or other device, it becomes so solidified, after a little time, that it will not loosen on removing the pressure, and much time and labor are involved in its removal and renewal.

Again, I am satisfied, from long experience, that any device for regulating the flow of oil must first filter the oil before it reaches the graduating-point, otherwise this point will become fouled and the cup inoperative.

In a cup, constructed as I have described, it is only necessary in most instances to release the screw and loosen the disks, putting in clean, fresh oil, and the cup operates well, turning down the screw again after a free flow has been established; and, again, when it is necessary to remove the points, it can readily be done.

I do not, as above remarked, claim any of the devices above alluded to; nor do I claim broadly a graduating oil-cup for lubrication; but—

What I do claim, as novel and useful, is—

1. The spring-bolt D, in the screw-cover of an oil-cup, made and operating substantially as described.
2. The combination of the bolt D and the screw E with the cover of an oil-cup.
3. The regulating-screw F, made with the tapering slot e, the spring-point d, and the broad, disk-like head, all made as described.
4. The packing of an oil-cup with fibrous disks, when these are not enclosed in a tube or chamber, and where they are threaded upon a slotted screw, which, at the same time, forms the compressing-agent for the fibrous disks, and a graduating-duct for admitting the oil into the duct in the stem of the cup by screwing into the same, all made and operating substantially as set forth and described, or their mechanical equivalents.

N. BANGS WILLIAMS.
